UNITED STATES PATENT OFFICE

HERBERT F. CAMPBELL, OF PHILADELPHIA, PENNSYLVANIA, ASSIGNOR TO PENNSYLVANIA CRUSHER COMPANY, OF NEW YORK, N. Y., A CORPORATION OF NEW YORK

CRUSHING MACHINERY

Application filed January 17, 1930. Serial No. 421,555.

My invention relates to crushing machinery of the type employing rotor structures carrying hammers which engage material delivered into their path and effect breakage or rupture

5 thereof by beating the same against a breaking surface forming one wall or part of one wall of the crushing chamber.

As set forth in the companion applications of George W. Borton, one of which was filed 10 December 12, 1929, under Serial No. 413,474, certain materials which may originally contain a high moisture content or which may be subject to wet conditions during transit between the point of excavation and the point 15 of crushing become so sticky that, in the operation of reducing the same, a mass of highly viscous mud builds up on the breaker plate and seriously affects the capacity of breaking machinery of this type.

20 The main object of my invention, therefore, is to provide means that will prevent this building up of a body of sticky or slimy material or mud upon the breaking surface or breaker plate.

25 A further object of my invention is to provide a sliding member arranged to be moved over the breaking surface or breaker plate against which the material is hurled by the rotary beaters or hammers.

30 A further object of my invention is to provide reciprocable scraper means movable across the face of the breaking surface or breaker plate which will serve to keep the same clean or substantially so during the 35 crushing operation. Such means may comprise one or more bars substantially in contact with the breaking surface during the reciprocating movements thereof.

40 A further object of my invention is to provide a movable scraper bar having teeth on its forward edge designed to cut through sticky material, mud and/or the like, that may accumulate at a point beyond the normal travel of a plain scraper bar and out of the range of 45 the beaters or hammers.

And a still further object of my invention is to provide flexible means for effecting reciprocal movement of the scraper bar or blade over the breaking surface or breaker 50 plate.

These and other features of my invention are more fully described hereinafter; reference being had to the accompanying drawings, in which:

Figure 1 is a cross sectional view of one 55 form of crushing structure with which the features of my invention may be employed; showing a movable scraper member associated with the breaking surface thereof.

Fig. 2 is a front elevation of the structure 60 illustrated in Fig. 1, and

Fig. 3 is a fragmentary view, in elevation, illustrating a detail of my invention.

While applicable to many forms of crushing machinery, in the present instance I have 65 shown my improved reciprocating scraper construction as applied to crushing machinery of the type illustrated in the pending application of George W. Borton, filed August 25, 1928, Serial No. 302,080, in which the crushing chamber is provided with a series of grid bars. These grid bars when employed may be carried by or associated with one wall of the crushing chamber so as to temporarily retard 70 large masses of material to be crushed which are acted upon by the uprunning hammers as 75 they pass between the grid bars.

In carrying out my present invention, I may associate with that part of the frame of the machine which may be termed the wall 80 of the crushing chamber and indicated generally at 1, a series of wear plates 2, which may be secured to said wall in any appropriate manner, as by the bolts 3. This breaking surface is inclined upwardly, partly overhanging the feed chamber and the rotor, and its lower portion may be curved to meet the curved wall of the crushing chamber.

Crushing machinery of this type is provided 85 with a hammer-carrying rotor structure of the character illustrated in the Borton application before referred to, and such rotor structure may include a shaft 5, suitably journaled, carrying disks 6, supporting rods 7, upon which hammers 8 are mounted. The wall 1 of the crushing chamber may support 90 a series of grid bars 9 between which the hammers pass, although it will be understood 95 that such grid bars may be omitted in the 100

use of the construction forming the subject of the present invention.

For the purpose of preventing any slimy or sticky portions of the material being crushed or reduced building up on the breaker plate or the breaking surface with which the hammers cooperate, and affecting the capacity of the machine, I have provided cleaning means in the form of a reciprocating 10 scraper member 10, which may be moved up and down over the breaker plate or the breaking surface while the material is being hurled against the same by the hammers.

In the construction illustrated in Figs. 1 15 and 2 of the drawings, a scraper blade is carried at the lower ends of flexible members, in the present instance chains 11, and guide-ways are provided for these chains in the form of guards 12 which may be carried by 20 the side walls of the crushing structure and secured thereto by bolts 12^a. The upper ends of these chains are connected to reciprocable rack bars 13 mounted in guide-ways 14, and motion may be imparted to these rack bars by 25 pinions 15 meshing therewith; such pinions being carried by a rock shaft 16 to which motion may be imparted in any suitable manner.

The scraper bar 10 may be provided with 30 relatively sharp edges 10^a and 10^b on the upper and lower portions of the same, so as to effect removal of any material tending to clog the breaking surface when moving in either direction. In order to increase the extent of surface of the breaker plate operated 35 upon by the scraping means, I may employ a plurality of these scraper bars, and in Figs. 1 and 2 I have shown a bar 10 at the lower end of the chains 11 and another bar spaced 40 a short distance above the same, indicated at 100. The scraper bars 10 and 100 are flexibly connected to the chain 11. In the present instance these bars are shown as spaced the distance of one link of the respective chains 11, but it will be understood that such spacing 45 may be altered, and that more than two scraper bars may be employed to keep the breaking surface clean, depending upon the extent of the same and the particular character 50 of the material operated upon.

As may be noted upon reference to Fig. 1 of the drawings, the lower wear plate of the breaking surface, (to which the grid bars when employed may be secured), has a portion more or less unaffected by the scraping action and/or by the action of the hammers, which may tend to clog with the sticky or slimy portions of the material operated upon. With a view of removing as much as possible 55 any accumulation of mud and/or other material that may occur at this point, when grid bars are employed, I may provide a scraper bar having depending teeth 17, such as illustrated in Fig. 3; which teeth may extend between the grid bars at their points of connec- 60

tion with the lower breaker plate or the wear plate support 2^a connected thereto and still be clear of the hammers. These teeth are preferably tapered toward their points and in addition they may have relatively sharp side edges. It will be understood of course that if the grid bars are omitted the lower scraper blade may have a movement of greater extent and pass over the wear plate indicated at 2^a. 70

The scraper bars may have a cross section substantially like that illustrated in Fig. 1, of the drawings or, if desired, the under side may be concaved so as to provide sharper edges. It will be understood, however, that I do not wish to be limited to this particular form of scraper bar, since other forms may be employed without departing from my invention; the important point being to provide a suitable form of reciprocable scraper bar 85 for operative engagement with the entire or substantially the entire breaking surface or the breaker plate and prevent objectionable accumulation thereon of mud and/or any sticky or slimy portion (or portions) of the 90 material operated upon. 95

It will also be understood that if any condition arises where the material contains hard rock or other material that might tend to damage the scraper bars, the latter may be held out of action by stopping the reciprocating movement of the rack bars when the chains are at their upper limit of travel; thereby holding the scraper blade or blades clear of the crushing zone. 100

I claim:

1. The combination, in crushing machinery, of a rotor structure having hammers, a breaking surface against which material undergoing crushing may be thrown by the action of said hammers, and a scraper bar or blade movable across the face of said breaking surface. 105

2. The combination, in crushing machinery, of a rotor structure having hammers, a breaking surface against which material undergoing crushing may be thrown by the action of said hammers, and a scraper bar vertically movable across the face of said breaking surface. 110

3. The combination, in crushing machinery, of a rotor structure having hammers, a breaking surface against which material undergoing crushing may be thrown by the action of said hammers, a scraper bar movable across the face of said breaking surface, and means for reciprocating said scraper bar. 115

4. The combination, in crushing machinery, of a rotor structure having hammers, a breaking surface against which material undergoing crushing may be thrown by the action of said hammers, and a plurality of spaced scraper bars movable across the face of said breaking surface. 120

5. The combination, in crushing machin- 125

ery, of a rotor structure having hammers, a breaking surface against which material undergoing crushing may be thrown by the action of the hammers, a plurality of spaced 5 scraper bars overlying the breaking surface, and means for reciprocating said scraper bars across said breaking surface.

6. The combination, in crushing machinery of the rotary beater type, of a rotor structure having hammers, a breaking surface against which material undergoing crushing may be thrown by the action of the hammers, a slideable scraper bar overlying the 10 breaking surface, and flexible means for reciprocating said scraping bar across said breaking surface.

7. The combination, in crushing machinery, of a rotor structure having hammers, a breaking surface against which material 20 undergoing crushing may be thrown by the action of the hammers, a slideable scraper bar having depending teeth overlying said breaking surface, and means for reciprocating said scraper bar.

25 8. The combination, in crushing machinery, of a rotor structure having hammers, a breaking surface against which material undergoing crushing may be thrown by the action of the hammers, a plurality of slideable scraper bars overlying said breaking surface; one of said bars having depending teeth, and means for reciprocating said scraper bars.

9. The combination, in crushing machinery, of a rotor structure having hammers, 35 a breaker plate against which material undergoing crushing may be thrown by the action of said hammers, a scraper bar, a pair of chains supporting said scraper bar, and means for imparting movement to said chains whereby the scraper bar may be reciprocated across the breaking surface.

40 10. The combination, in crushing machinery, of a rotor structure having hammers, a breaker plate against which material undergoing crushing may be thrown by the action of said hammers, a scraper bar, a pair of chains supporting said scraper bar, slideable rack bars connected to said chains, pinions engaging said rack bars, and means for imparting movement to said pinions whereby the scraper bar may be reciprocated across the breaking surface.

45 11. The combination, in crushing machinery, of a rotor structure having hammers, a breaker plate against which material undergoing crushing may be thrown by the action of said hammers, a scraper bar, a pair of chains supporting said scraper bar, guide-ways for said chains, slideable rack bars connected to said chains, pinions engaging said rack bars, and means for imparting movement to said pinions whereby the scraper bar may be reciprocated across the breaking surface.

50 12. The combination, in crushing machin-

ery, of a rotor structure having hammers, a breaker plate against which material undergoing crushing may be thrown by the action of said hammers, a scraper bar, a pair of chains supporting said scraper bar, guide-ways for said chains, rack bars connected to said chains, housing guide-ways for said rack bars, pinions engaging said rack bars, and means for imparting movement to said pinions whereby the scraper bar may be reciprocated across the breaking surface.

55 13. The combination, in crushing machinery, of a rotor structure having hammers, a curved breaking surface against which material undergoing crushing may be thrown by the action of said hammers, a scraper bar movable across said curved breaking surface, and driven chains connected to said scraper bar and serving to impart movement to the same.

60 14. The combination, in crushing machinery, of a rotor structure having hammers, a curved breaking surface against which material undergoing crushing may be thrown by the action of said hammers, a scraper bar movable across said curved breaking surface, driven chains connected to said scraper bar for imparting movement thereto, and curved guide-ways disposed at the sides of the breaking surface for said chains.

65 15. The combination with a crushing machine of the rotary hammer type having a crushing chamber and a breaking surface co-operating with the hammers for the crushing of material, of a scraper bar or blade movable over said breaking surface for the purpose of cleaning the same.

70 16. The combination with a crushing machine of the rotary hammer type having a crushing chamber and a breaking surface against which material undergoing crushing may be thrown by the action of the hammers, of a scraper bar or blade for cleaning said breaking surface and mounted for movement with respect to the same.

75 17. The combination with crushing machinery of the rotary hammer type having a crushing chamber and a breaking surface co-operating with the hammers in the crushing of material introduced into said crushing chamber, of a reciprocable scraper bar or blade mounted for movement over said breaking surface.

80 18. The combination with crushing machinery of the rotary hammer type having a crushing chamber and a breaking surface against which material undergoing crushing may be thrown by the action of the hammers, of a scraper bar or blade reciprocally movable over said breaking surface for the purpose 125 of cleaning the same.

In witness whereof I have signed this specification.
